UNITED STATES PATENT OFFICE.

FRITZ KILIAN, OF BERLIN-LICHTENBERG, GERMANY, ASSIGNOR, BY MESNE ASSIGNMENTS, TO THE CHEMICAL FOUNDATION, INC., A CORPORATION OF DELAWARE.

ROTATING OR REVOLVING PRESS.

Application filed October 15, 1917. Serial No. 196,774.

To all whom it may concern:

Be it known that I, FRITZ KILIAN, subject of the King of Prussia, residing at Berlin-Lichtenberg, Germany, Herzbergstr. 5 102-104, have invented certain new and useful Improvements in and Relating to Rotating or Revolving Presses, of which the following is a specification.

The present invention relates to improvements in revolving or rotating presses for the treatment of pulverulent material in which the pressing cylinders are arranged in the rim of a rotatable disk in the form of radial bores.

In presses of this kind, as heretofore constructed, the abutment or the counter bearing for the pressure exerted on the material has been in the form of an endless chain, the single links of which were caused to bear 15 successively against the openings of the press cylinders and to move with the latter for a certain distance. Such devices have been complicated and there was consequently considerable wear of the movable parts of 20 the chain, especially in view of the character of the material operated on; and it has been difficult to insure that the desired pressure would be effective during a definite period of time. It has also been proposed to provide disk-like bodies rolling along the rotating or revolving press cylinders with counter dies which for the purpose of effecting a preliminary pressing have to enter 25 the radial bores from the outside. In this case it is difficult to arrange the parts so that the counter dies will fit closely and accurately in the mouths of the cylinders on account of the gear wheel like engagement 30 of the said parts. Furthermore the device in such a case is subjected to considerable wear.

According to the present invention, the counter bearing or abutment against which the pressure devices act consists of a smooth 45 surfaced rotating or revolving body bearing against the outer face of the rim containing the press cylinders, said body being rotated together with the said rim. The rotating counter bearing closes the press cylinders 50 only when pressure is being exerted on the contents thereof and rolling friction only occurs between the said bearing and the carrier of the press cylinders.

In the accompanying drawings:

Figure 1 is a cross section, and

Figure 2 is a longitudinal section taken on the line A—B of Figure 1.

In a frame 1 consisting of two parts a disk 2 is journalled having, in the embodiment illustrated, a single laterally projecting flange 3, although it will be obvious that such flange might, if desired, be duplicated on the other face of the disk. Upon the shaft 4 of the disk 2, gear wheel 5 is arranged which meshes with a corresponding gear wheel mounted on the shaft 7 of a second disk 6, Figure 2. The shaft 7 of the disk 6 carries a driving crank 8, which in the example shown is in the form of a hand crank, but which may be replaced by any suitable mechanical drive.

In the rim 3 of the disk 2 are formed a series of radial bores 9 constituting the pressing matrices, only a few of which are shown in the drawings, others being indicated by dash and dotted lines. To the example shown, only one row of matrice bores 9 is provided, but if the parts 2, 3 are made of sufficient width, a plurality of rows of bores 9 side by side may be provided.

In each of the bores 9 is arranged a die 10 that is connected to a suitable stem having at its inner end a head 11 that cooperates with the means for reciprocating the die. In the form of the invention illustrated, said die controlling means includes three rollers 12, 13 and 14 and the rail or guide members 15, 16 and 17 arranged between the said rollers.

At the outer periphery of the rim 3 a hopper 18 is provided from which the matrices 9 moving underneath the said hopper, receive their charges.

A pressure block 19 tightly bearing against the rim 3 is joined to the hopper 18, being mounted in a bridge 20. Underneath the pressure block 19 a roller 12 is arranged, the dimensions of which are chosen in such a manner, that each of the dies running over the said roller is moved outwardly for a certain distance so that the filling in the corresponding matrices, receives a preliminary pressing against the part 19.

After leaving the rollers 12 each of the dies 10, 11 moves over the rail member 15 to a roller 13 without changing its position with regard to the rim 3, the roller 13 imparts a slight additional outward movement to the dies, the pressure of which is resisted by the disk 6 rotating with the disk 3. The

roller 13 effects the last outward moving of each die, that is to say finishes the pressing operation. If the positions of the dies before reaching the hopper 18 and in engagement with the roller 13 are compared with each other, it will at once be seen that a very great compression of the material within the matrices or bores has taken place. If the diameter of the matrices is correspondingly small and the diameter of the disks 3 and 6 comparatively large, a perfectly satisfactory closure of the matrice openings will be effected by the rotating body 6.

From the roller 13 the dies are carried along over the rail or guide member 16 and to a roller 14, which imparts further outward movement thereto, so that the compressed material drops out of the matrice bores, into a chute 21. In passing from the roller 14 to the hopper 18 each die must be moved inward, so that the corresponding matrices may receive a fresh charge. This is effected by the rail member 17 the outer guide ledge of which grips over the die heads 11 and thereby retracts the dies. The rail member 17 is adjustably mounted at 22, so that the depths of the matrices and amount of each charge of material may be altered if desired.

During the main pressing operation by the roller 13, rolling friction occurs between the matrice filling and the counter bearing 6. During the preliminary pressing by the roller 12, the counter bearing is formed by a fixed part 19, so that in this case sliding friction takes place between the filling and the said part 19. This seems to be immaterial, as the pressing force at this place is still considerably low. A rotating body 40 could of course also be used opposite the roller 12, as a counter bearing if desired.

Having thus described the invention, what is claimed is:

1. In a rotary press for pulverulent material, the combination of a rotary body provided with a plurality of peripheral matrices, a die or plunger within each matrix, a smooth surfaced revolving cylindrical abutment bearing against said rotary body and adapted to successively close matrices therein at the practical conclusion of the first 90° of rotation of said rotary body, said cylindrical abutment cooperating with means within said rotary body adapted to positively force outward the die or plunger in the matrix closed by said abutment.

2. In a rotary press for pulverulent material, the combination of a rotary shell having a plurality of radial bores therein forming peripheral matrices, a die or plunger in

each matrix having its stem extending through the bore to the interior of the shell, a smooth surfaced revolving, cylindrical abutment bearing against the outer surface of the shell and adapted to successively close 65 matrices therein at the practical conclusion of the first 90° of rotation of said rotary body, said cylindrical abutment cooperating with a roller arranged within the shell and adapted to engage the inner end of the 70 plunger in the matrix closed by said abutment and to force said plunger outward.

3. In a rotary press for pulverulent material, the combination of a rotary shell having a plurality of radial bores therein forming peripheral matrices, a die or plunger in each matrix having its stem extending through the bore to the interior of the shell, a plurality of rollers arranged within the shell and adapted to successively move the 80 plungers radially outward gradually increasing distances as the shell rotates, a fixed abutment adapted to close the matrix opposite one of said rollers and act as a counter bearing for the pressing force exerted thereby, a smooth surfaced revolving cylindrical abutment cooperating in a similar manner with another of the rollers, and means adjustably mounted for positively moving the plungers inwardly of the shell after passing 85 the last of said rollers.

4. In a rotary press for pulverulent material, the combination of a rotary shell having a plurality of radial bores therein forming peripheral matrices, a die or plunger in each matrix having its stem extending through the bore to the interior of the shell, said plungers being fitted with a head member at their inner end, a plurality of rollers arranged within the shell and adapted to 100 successively move the plungers radially outward gradually increasing distances as the shell rotates, a fixed abutment adapted to close the matrix opposite one of said rollers and act as a counter bearing for the pressing force exerted thereby, a smooth surfaced revolving cylindrical abutment cooperating in a similar manner at the practical conclusion of the first 90° of rotation with another of the rollers, and a rail member adjustably mounted for positively moving the plungers 105 inwardly of the shell after passing the last of said rollers.

In testimony whereof I affix my signature in presence of two witnesses.

FRITZ KILIAN.
